OUTDOOR LUMINAIRE

William S. Akely, Elmwood Park, Ill., assignor to Guardian Light Company, Oak Park, Ill., a corporation of Illinois

Filed July 5, 1962, Ser. No. 70,797

Term of patent 14 years

(Cl. D48—31)

FIG. 1 is a bottom perspective view of an outdoor luminaire showing my new design wherein the lens panel is corrugated and translucent;

FIG. 2 is an end elevational view of the luminaire taken from the mounting end with portions omitted for ease of illustration;

FIG. 3 is a side elevational view thereof as shown in FIG. 1;

FIG. 4 is a top plan view thereof as shown in FIG. 1;

FIG. 5 is a sectional view taken approximately along line 5-5 in FIG. 4;

FIG. 6 is a front end elevational view of the luminaire of FIG. 1;

FIG. 7 is a bottom perspective view of a second embodiment of the luminaire shown in FIG. 1 wherein the lens panel is smooth and transparent;

FIG. 8 is an end elevational view of the luminaire shown in FIG. 7 taken from the mounting end with portions omitted for ease of illustration;

FIG. 9 is a side elevational view of the luminaire of FIG. 7;

FIG. 10 is a top plan view of the luminaire shown in FIG. 7;

FIG. 11 is a sectional view taken approximately along line 11-11 in FIG. 10; and

FIG. 12 is a front end elevational view of the luminaire of FIG. 7.

The dominant features of my design reside in the portions shown in full lines. The light tubes and supports are shown in broken lines for illustrative purposes only.

I claim:

The ornamental design for an outdoor luminaire, substantially as shown and described.
